UNITED STATES PATENT OFFICE.

ORA R. FOWLER, OF SAGINAW, MICHIGAN, ASSIGNOR TO FRANK G. PALMERTON, OF SAGINAW, MICHIGAN.

METALLIC COVER.

No. 922,270.

Specification of Letters Patent.

Patented May 18, 1909.

Application filed May 23, 1908. Serial No. 434,581.

To all whom it may concern:

Be it known that I, ORA R. FOWLER, a citizen of the United States, residing at Saginaw, in the county of Saginaw and State of Michigan, have invented certain new and useful Improvements in Metallic Covers; and I do hereby declare the following to be a full, clear, and exact description of the invention, such as will enable others skilled in the art to 10 which it appertains to make and use the same.

My invention relates to metallic covers for pails and other receptacles equipped with bails.

15 One object is to provide a cover having a recessed or cutaway portion to afford a clearance for the bail and its connected parts.

Another object is the provision of a cover which is unbreakable, which will not split 20 and which cannot be surreptitiously removed and replaced without leaving an indication of such removal.

Still another object is to make a strong, dust and dirt proof cover which will permit 25 the receptacles to be superimposed one upon the other and will maintain the contents of the receptacles clean and fresh.

The cover is more particularly designed 30 for pails adapted to contain candy, lard, jelly, syrup, grease, stock-foods and the like.

In the candy trade particularly the pails have been closed with wooden covers. These pails are manufactured with the bail attached, the covers being loose or separate.

35 The candy manufacturer purchases a stock of pails and after filling these with candy, secures the covers in place with nails or double pointed tacks. Frequently, the wooden covers split when being fastened on, which often 40 makes it necessary to remove the broken cover and substitute a new one therefor, resulting in a loss of time and money because the broken cover cannot be used again. The greatest disadvantage, however, results

45 from the fact that draymen or railroad men will pry open the cover or remove a piece thereof, and help themselves to the contents, afterward replacing the cover. The consignee of, say one or two hundred pails will 50 receipt for them in good order, thus releasing the railway company. The small retailer,

however, on receiving a pail which does not contain a full amount of candy, (generally about 30 lbs.) promptly deducts the cost of 55 the candy removed, from the amount of his bill, which deducted amount must be set

down to profit and loss by the wholesaler and often represents the amount of his profit from the sale. Often, too, the wooden covers break in transit owing to the superimposed weight of other pails, which permits the railway employees to help themselves to the contents. My object in using a metallic cover is to prevent these claims for shortage because the cover cannot be removed and 60 replaced without indicating that the contents has been tampered with owing to the fact that the fastenings once removed and replaced remain loose.

My cover will permit pails to be stacked 70 one on top of the other without breakage and furthermore, may be used by the retailer to exclude dust, dirt and other extraneous material from the goods, after the package has been opened.

75 In the accompanying drawings, Figure 1 is a side view showing my invention applied to a pail. Fig. 2 is a cross-sectional view through the cover and Fig. 3 is a top plan view.

80 The cover comprises a depressed head A provided with radiating corrugations (1), (1), to strengthen the cover. The periphery of the head is equipped with an upwardly projecting or raised wall (2) terminating at its upper edge in an outwardly projecting annular ring (3) from the outer circumference of which depends a flange (4). This construction forms an inverted annular groove adapted to receive the upper edge of 85 the pail.

85 In my construction, I am enabled to make the cover of a comparatively light weight sheet metal because the radiating corrugations afford the necessary strength. The 90 height of the wall (2) is but slight as the pails are filled nearly full and the head setting down in the pail would, by engaging the contents, prevent the cover from seating properly if the wall was deep.

100 While others may have devised covers similar to that above described, such covers are not adapted for application to pails or other receptacles provided with bails for the reason that the depending flanges will catch upon 105 the ears or eyes of the bail, or crowd the bail itself so as to render it useless.

110 Users of pails have long desired a cover which will prevent theft, which will be strong and durable, and which will serve to keep the contents clean and fresh. The above described cover, however, could not

be applied to a pail because of the presence of the bail. It is my intention to provide a cover of this nature which can be so applied and to this end, I recess or cut away the depending flange (4) at diametrically opposite points, as at (5) to afford a clearance for the ears to which the bail is attached, to accommodate the eyes of the bail as the latter is moved in the arch of a circle and to avoid crowding the bail itself. The particular shape of recess is semi-circular as shown, which avoids the formation of sharp corners, liable to be bent outward and interfere with the operation of the bail. The recess is cut high enough to permit the eye of the bail to clear the cover throughout the movement of the bail.

The cover may be fastened to the pail by nails or double pointed tacks in the same manner and with the same tools as are now employed in fastening wooden covers in place. The inverted groove and depressed head constitute a firm seat and the package is practically air and dirt proof.

In shipping, the covers may be nested one within the other to occupy a minimum of space, and when applied to the pails, the bottom of one pail fits within the upstanding wall (2) on the cover, thus economizing space, the covers by reason of the corrugations being strong enough to support several pails.

Another great advantage resulting from recessing the flange is that it makes the flange flexible. The pail openings do not always run exactly even and a cover having an unrecessed depending flange could not be made to fit pails differing slightly in the size of their openings, but any cover equipped with its recessed flange can be placed on such pails with ease because of the yield and flexibility of the flange and the fact that the inner wall

(2) is of but slight depth. This also facilitates the nesting of the covers.

Another advantage arising from the use of 45 a cover having a recessed outer flange, as described, is that the cover can only be put on the pails in one position, namely, with the recesses above the ears. This prohibits an unauthorized person from entirely removing 50 the cover, removing a part of the contents and replacing the cover without detection because the fastenings will remain loose after the cover has once been removed and the cover cannot be turned to bring a new surface for the fastening means to take into. Also if the fastening means are removed from their original positions the holes in the cover will disclose the fact that the goods have been 55 tampered with.

The cover is of such rigidity that when one fastening is removed the cover cannot be flexed or bent to allow the removal of the contents of the package.

Having thus fully disclosed my invention, 65 what I claim as new is:—

The combination with a pail having ears thereon, and a bail, the ends of the bail connected to the ears, of a cover having a depressed corrugated head, a raised wall around 70 the periphery of the head, an outwardly projecting ring carried by the wall, and a flange depending from the ring and overlying the outer face of the pail, the flange only being recessed and lending flexibility to the cover, 75 the ears and the ends of the bail being afforded clearance by the recesses in the flange.

In testimony whereof, I affix my signature in presence of two witnesses.

ORA R. FOWLER.
